Franklin B. Hunt

United States Patent Office.

FRANKLIN B. HUNT, OF RICHMOND, INDIANA.

Letters Patent No. 96,004, dated October 19, 1869.

IMPROVEMENT IN STRAW-CUTTERS.

The Schedule referred to in these Letters Patent and making part of the same.

To all whom it may concern:

Be it known that I, FRANKLIN B. HUNT, of Richmond, in the county of Wayne, in the State of Indiana, have invented a new and improved Mode of Adjusting the Cutter-Bars of Feed-Cutters; and I do hereby declare that the following is a full and exact description thereof, reference being had to the accompanying drawings, and to the letters of reference marked thereon, in which—

Figure 1 is a top view of the bearing-bar, lower halves of journal-boxes to the cutter-shaft, side plates, and cutter-bar attached thereto.

Figure 2 is a side view of the same.

In figs. 1 and 2—

C is a bearing-bar.

B is the lower halves of the journal-boxes to the cutter-shaft.

A is side plates, having slots F, in which the upper feed-roll works.

D is an adjustable cutter-bar, in which are slots, through which the bolts E E pass, and also through the bearing-bar C.

The bolts E are secured by nuts underneath the supporting-bar C.

a a are adjusting-keys to the adjustable cutter-bar D.

The bearing-bar C has suitable slots made in it, to receive the keys a a, and admit of their being adjusted.

G G are bevelled slots, to which the heads of the bolts E E are fitted, said slots being elongated, to admit of the bar D moving beneath the heads of the bolts E, in order to adjust it to the edge of the knife.

The operation of the adjustment of the bar D is thus:

The bar D is first brought into approximate adjustment to the cutter-knife, and secured by the bolts E E, after which the precise adjustment is effected by tapping or pressing down the keys a a.

The keys a a, after having been made to adjust the bar D, will hold it firmly to its place, and prevent it from being forced backward by the action of the cutter-knife.

Other means could be substituted for holding the adjustable bar, against which the knife cuts, from slipping back, such as set-screws, working through a threaded lug, so that the end of the screw would press against the back of the bar, or the wedges a a may be so changed that they may lie horizontally at the back of the bar, suitable provision being made for them on the bed-piece.

Having thus described my invention,

What I desire to secure by Letters Patent, is—

1. Securing the adjustable cutter-bar D to the bearing-bar C, by means of bolts E E, the heads of which are fitted in the elongated slots G G, as and for the purpose described.

2. The adjusting-keys a a, or their equivalents, in combination with the adjustable bar D, provided with vertical bolts, to hold it to its bed or bearings, substantially as and for the purpose shown and set forth.

FRANKLIN B. HUNT.
